UNITED STATES PATENT OFFICE.

THOMAS J. LOVETT, OF CHICAGO, ILLINOIS, ASSIGNOR, BY MESNE ASSIGNMENTS, TO THE INTERNATIONAL ORE SEPARATING COMPANY, OF NEW JERSEY.

MAGNETIC SEPARATOR.

SPECIFICATION forming part of Letters Patent No. 486,879, dated November 29, 1892.

Application filed February 13, 1892. Serial No. 421,429. (No model.)

To all whom it may concern:

Be it known that I, THOMAS J. LOVETT, a citizen of the United States, residing at Chicago, in the county of Cook and State of Illinois, have invented certain new and useful Improvement in Magnetic Ore-Separators; and I do hereby declare the following to be a full, clear, and exact description of the invention, such as will enable others skilled in the art to which it appertains to make and use the same.

My invention relates to that class of magnetic separators in which an endless belt runs over a drum, within which there is a rotating magnet. In large machines it would become necessary to drive an ordinary two-pole magnet at a very high speed in order to secure the necessary number of reversals of polarity, and the magnet would also become large and unwieldy. To avoid this I employ a wheel with a number of small magnets in its periphery. These magnets alternately present their north and south poles at the outer surface of the wheel.

In the drawings, Figure 1 is a section through the main frame, showing the working parts of my invention in side elevation. Fig. 2 is a diagram of the electrical connections. Fig. 3 is a central section through wheel and drum. Fig. 4 is a section through the drum, showing the wheel and a portion of the belt in side elevation.

In all the figures the same part is represented by the same reference-figure. 1 is the main frame, in which are journaled the drum 2 and the idler-pulley 3. The endless belt 4 runs over these. Within the drum 2 and revolving upon the same axis is the wheel 5, containing a plurality of magnets 12, set in its periphery. The inclined feed-chute 6 is arranged tangentially to the drum and magnetic wheel. The shaking table 7 is mounted on the shaft 8 and vibrated by the arm 9, which rests on the pins 10, set in the disk 11, which forms one end of the drum 2. The drum 2 is composed of two disks 11 11^a, connected together by brass rods or by a cylinder of some non-magnetic material, and revolves freely upon the shaft 15. Rotation is given to it by the gear 17, mounted on the sleeve 16. The gear 18 rotates the magnetic wheel, which consists of the disks 13 14, keyed to the

shaft 15 and holding the magnets 12. These magnets may be of any construction so long as they present alternate north and south poles at the external surface of the wheel. Wires run from the magnets to the collecting-rings 19 and 20, through which current is supplied. The wires might be connected in various ways. The arrangement shown in full lines in Fig. 2 shows all the magnets connected in multiple arc from the two leading-in wires 23 and 24. In dotted lines the sixteen magnets are shown divided into four sets of four each, with each set connected in series by wires 26 and supplied with current by leading-in wires 25 and 27 from the collecting-rings 21 22.

In operating my invention a much more rapid rate of rotation is given to the magnetic wheel than to the drum and to the belt which runs on the drum. This is indicated by the gear 18 being of much less diameter than gear 17. Consequently a line of particles going up on the belt 2 are first subjected to the action of one of the magnets 12, which presents its north pole, and then to the action of the next magnet, which presents its south pole, and so the stuff is subjected to rapid magnetic changes, which keep it continuously alive. The vibration of the shaking table 7 keeps a steady supply of crushed ore going into the feed-chute 6.

Having therefore described my invention, what I claim as new, and desire to protect by Letters Patent, is—

In a magnetic separator, the combination of a wheel which has a plurality of magnets set in its periphery with alternate north and south poles pointing outward, a drum which surrounds said wheel, an idler-pulley, an endless belt which runs around said pulley and drum, mechanism for rotating said wheel and drum at different rates of speed, and an inclined feed-chute arranged tangentially to said wheel and drum, substantially as described.

In testimony whereof I affix my signature in presence of two witnesses.

THOMAS J. LOVETT.

Witnesses:

WARREN W. FOSTER,
A. P. SMITH.
